UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed July 31, 1930. Serial No. 472,167.

My invention relates to railway cars and has for its object the provision of improved means adapted to be associated with the roof of a railway box car for supporting a load 5 lifting device whereby automobiles and other heavy and cumbersome lading may be moved into or out of the car or elevated within the car.

A primary feature of the invention consists in providing the car with transversely 10 extending members having laterally projecting flanges spaced beneath the roof sheets and in associating therewith a channel shaped beam which extends longitudinally of the 15 car and is rigidly secured to the flanges of the said members, the beam being provided with transversely extending means forming therewith structures of box-like section and adapted to serve as a support for a load lifting device.

Another feature of the invention consists in providing the car with a plurality of transversely extending members rigidly secured to the carlines, each of said members having 25 a flange spaced below the roof sheets, and a plurality of beams extending longitudinally of the car on opposite sides of said members, each of said beams being of channel shape and having secured thereto transversely extending means, each of said means forming 30 with the associated beam a structure of box-like section and being adapted to serve as a support for a load lifting means.

A further feature of the invention consists 35 in providing the roof with a plurality of longitudinally extending beams, each of which is provided with a web portion and downwardly extending legs terminating in lateral flanges, the web of each beam being in supporting engagement with the underside of adjacent roof sheets of the car and the flanges 40 of the beam being respectively secured to members which extend transversely of the car and are secured to adjacent carlines 45 thereof.

Other and more specific features of the invention residing in advantageous forms, combinations and relations of parts will hereinafter appear and be pointed out in the 50 claims.

In the drawings illustrating a preferred embodiment of the invention:

Figure 1 is a longitudinal sectional view of the upper portion of a railway box car.

Figure 2 is a fragmentary sectional view 55 taken on line 2—2, Figure 1.

Figure 3 is an enlarged fragmentary sectional view taken on line 3—3, Figure 1.

Figure 4 is a sectional view taken on line 4—4, Figure 3.

Referring more particularly to the drawings illustrating a rigid type of roof 1 and 2 indicate the rigidly connected side and end plates. The roof sheets which may conveniently extend continuously from one side of 65 the car to the other are designated by the reference numeral 3 and each of them, with the exception of the end roof sheets, that is, the sheets adjoining the end plates 2 are formed with upturned side marginal flanges 70

4. One side edge of each of the end roof sheets is formed with a similar flange but the opposite edge of the sheet is formed with a downturned flange 5 for attachment by rivets 6 to the upper portion of the adjacent 75 end plate. At their eaves edges the roof sheets are preferably formed with downturned flanges 7 for attachment by rivets 8 to adjoining portions of the side plates 1.

The adjacent upturned flanges 4 of adjoining roof sheets are embraced by and rigidly secured by rivets 9 to carlines 10. Each of the carlines is of substantially U-shape having downwardly extending legs 11 which terminate in oppositely disposed laterally 85 projecting flanges 12, the latter being disposed in overlapping relation to adjacent portions of the roof sheets. The carlines may advantageously decrease progressively 90 in depth from adjacent the ridge of the roof and at their ends they are preferably flanged downwardly for attachment to the side plates by the roof sheet securing rivets 8.

Interposed between the legs of each carline and the associated flanges of adjoining roof sheets is a transversely extending member 13 of T-shape having a stem 14 and a flange 15. The stem of each T-shaped member is secured to the associated carline and adjacent roof sheet flanges by the rivets 9 100

and the flange 15 is spaced below the roof sheets. As may be seen from the drawings the portion of the flange adjacent the ridge of the roof is disposed in a substantially horizontal plane and is spaced a greater distance below the roof sheets than the portions of the flange adjacent the ends of the member which are disposed in a plane substantially parallel with that of the roof sheets. To rigidly connect the members to the side plates brackets 16 may be employed respectively having a portion 20 secured by the rivets 8 to the side plates and having a portion 21 interposed between adjacent portions of the roof sheets and flanges 15 of the members for attachment to the latter by rivets 22.

Extending longitudinally of the car on opposite sides of the members 13 are a plurality of beams 23. Each of these beams is preferably of channel shape having a web portion 24 and downwardly extending legs 25 terminating in oppositely disposed laterally projecting flanges 26. Each of the beams is so proportioned that its flanges 26 may be secured by rivets 27 in overlapping relation to the flanges 15 of adjacent members 13 while its web 24 is arranged in supporting engagement with the underside of the roof sheet intervening between the members to which it is secured. The beams adjacent the ends of the car are connected to the end plates by angle shaped brackets 28, each of which is formed with a flange 29 for attachment by rivets 30 to the adjoining end plate and a flange 31 for attachment by rivets 32 to the lateral flanges 26 of the associated beam.

Each of the beams is provided with one or more transversely extending members 33. These members are each formed with a substantially horizontal plate portion 34 and downwardly extending marginal flanges 35, the plate portion being rigidly secured by rivets 36 to the flanges 26 of the associated beam. The plate portion of each of the members 33 is spaced a sufficient distance from the web 24 of its associated beam to permit a rope, chain, nose of a hook, or any other suitable means capable of supporting a load lifting device to be inserted in the space or opening defined by the web 24 and plate portion 34. It will be perceived that by securing the members 33 to the beams in the manner disclosed they form therewith structures of box-like section whereby the beams are greatly rigidified so as to more efficiently withstand the forces imparted to them from the load lifting devices.

The foregoing construction results not only in simple and rugged means for cooperating with load lifting devices but the longitudinally extending beams 23 are associated with the roof structures in such manner that they function as a ridge pole in that they serve to

brace the roof and to support the roof sheets.

I claim:

1. A roof for railway cars involving a plurality of roof sheets having marginal flanges along their side edges, carlines respectively secured to adjacent flanges of neighboring roof sheets, members extending transversely of the car and respectively secured to said carlines, each of said members having a laterally projecting flange spaced beneath said roof sheets, a channel shaped beam extending longitudinally of the car between said members and rigidly secured to the flanges of said members, and means rigidly secured to said beam and forming therewith a structure of box-like section, said means being adapted to serve as a support for a load lifting device. 70 75 80

2. A roof for railway cars involving a plurality of roof sheets having upstanding marginal flanges along their side edges, carlines respectively embracing and rigidly secured to adjacent flanges of neighboring roof sheets, a transversely extending member rigidly secured to each carline and the flanges of the roof sheets associated with the latter, each of said members having a laterally extending flange disposed in spaced relation to the underside of the roof sheets, a channel shaped beam extending longitudinally of the car between said members and resting upon the flanges of the latter, and means rigidly secured to said beam and forming therewith a structure of box-like section, said means being adapted to serve as a support for a load lifting device. 85 90 95 100 105 110 115 120

3. A roof for railway cars involving roof sheets having upstanding side marginal flanges, T-shaped members respectively interposed between adjacent flanges of neighboring roof sheets, the flange of each T-shaped member being spaced below said roof sheets, U-shaped carlines respectively embracing the adjacent flanges of neighboring roof sheets and rigidly secured to the latter and to said members, a channel shaped beam extending longitudinally of the car between said members and rigidly secured in overlapping relation to the flanges of the latter, and means rigid with said beam adapted to serve as a support for a load lifting device, said means extending transversely of the beam and forming therewith a structure of box-like section. 110 115 120

4. A roof for railway cars involving a plurality of roof sheets having upturned side marginal flanges, carlines respectively secured to adjacent flanges of neighboring roof sheets, members respectively interposed between adjacent flanges of neighboring roof sheets and extending transversely of the car, and a beam member extending longitudinally of the car between said members in supporting engagement with the underside of adjacent roof sheets, said beam being of channel 125 130 135 140

shape and provided with a transversely extending member forming with the beam a structure of box-like section, said transversely extending member being adapted to serve 5 as a support for a load lifting device.

5. A roof for railway cars involving a plurality of roof sheets having upstanding marginal flanges along their side edges, U-shaped carlines embracing the adjacent flanges of 10 neighboring roof sheets and having oppositely disposed laterally extending flanges overlapping adjoining portions of the roof sheets, and members extending transversely of the car and respectively interposed between the 15 adjacent flanges of neighboring roof sheets, each of said members being formed with a laterally extending flange, a beam extending longitudinally of the car between said members and rigidly secured to the flanges of the 20 latter, and means extending transversely of the beam and rigidly secured thereto, said means forming with the beam a structure of box-like section and being adapted to serve as a support for a load lifting device.

25. 6. A roof for railway cars comprising a plurality of carlines, transversely extending members rigidly secured to and depending below said carlines, each of said members being provided with a laterally extending 30 flange, and a channel shaped beam extending longitudinally of the car between said members, said beam being provided with oppositely disposed laterally extending flanges respectively secured in overlapping relation 35 to the flanges of said members, and means extending transversely of said beam and rigidly secured to the flanges thereof, said means forming with the beam a structure of box-like section and being adapted to serve as a 40 support for a load lifting device.

45. 7. A roof for railway cars involving a plurality of roof sheets having upturned marginal flanges along their side edges, carlines respectively embracing and rigidly secured to adjacent flanges of neighboring roof sheets, members extending transversely of the car and respectively secured to said carlines, a channel shaped beam member extending longitudinally of the car between 50 said members, said beam being rigidly secured to the latter and having a web portion in supporting engagement with the underside of an adjoining roof sheet, and means extending transversely of said beam and rigidly secured thereto, said means forming 55 with the beam a structure of box-like section and being adapted to serve as a support for a load lifting device.

60. 8. A roof for railway cars involving a plurality of roof sheets having upstanding side marginal flanges, carlines respectively embracing adjacent flanges of neighboring roof sheets, members extending transversely of the car and respectively secured to said carlines, each of said members having a laterally 65

projecting flange disposed in spaced relation to the underside of the roof sheets, a channel shaped beam extending longitudinally of the car between said members, said beam having a web portion in supporting engagement 70 with an adjacent roof sheet and having oppositely disposed laterally projecting flanges rigidly secured to the flanges of said members, and means extending transversely of the beam and rigidly secured to the lateral 75 flanges thereof, said means forming with the beam a structure of box-like section and being adapted to serve as a support for a load lifting device.

90. 9. A roof for railway cars involving a plurality of carlines, T-shaped members extending downwardly from said carlines, the stem of each of said T-shaped members being rigidly secured to the adjacent carline and the flange of each of said members being disposed below the carlines, and a plurality of beams extending longitudinally of the car in alinement with each other, each of said beams being of channel shape and extending continuously between neighboring members, 95 said beams being rigidly secured to the flanges of said members and provided with transversely extending means adapted to serve as a support for a load lifting device, each of said means forming with the associated beam a structure of box-like section.

In testimony whereof I affix my signature.
EARL R. SWANSON.
